AGITATOR FOR CASCADE EVAPORATORS

Charles Richard Percival Cash, Canton, N. C.

Application November 21, 1942, Serial No. 466,513

2 Claims. (Cl. 159—10)

1

This invention relates primarily to apparatus for recovering chemicals from black liquor obtained in the preparation of wood pulp by the sulphate or caustic soda process.

The paper pulp is made in the sulphate process by treating chips of wood with sodium hydrates or sodium sulphite. After the action of the chemicals on the wood has been completed in the digester, the material is washed and the wash liquor, usually termed black liquor, contains substances which should be recovered for reasons of economy. In the usual process the black liquor solution is carried through a multiple effect evaporator and thence through a so-called cascade evaporator within which a further portion of the water is evaporated by means of hot gases until the liquor is of a relatively heavy density. The cascade evaporator comprises a plurality of rotating baffle wheels mounted within a chamber. The bottom of this chamber contains a pool of liquor into which the wheels having baffle plates dip as they rotate. Hot gases flow through the top of the chamber and over the wheels to evaporate moisture from the liquor which has adhered to the baffle plates. By thus evaporating water from the liquor wetting the wheels the density of the pool of liquor is increased.

It has been found that in the spaces between adjacent groups of wheels and the wheels and the corners of the chamber there is substantially no agitation of the liquor and consequently lumps congeal and form into piles there. These piles must periodically be removed or they will seriously interfere with the rotation of the wheels.

It is an object of this invention to provide means for continuously agitating and moving the liquor in currents within the cascade evaporator thereby preventing lump accumulations in piles and assuring the continuity of operation of the evaporator.

In the accompanying drawings:

Figure 1 is a sectional elevation on line 1—1 in Figure 2 of a cascade evaporator embodying the invention.

Figure 2 is a plan view corresponding to Figure 1.

The cascade evaporator comprises a closed tank 10 within which are four groups of baffles 12, 13, 14 and 15. Since the construction of cascade evaporators is generally known it need only be mentioned that the individual baffles 16 (Fig. 1) of each group 12 to 15 are attached at their ends to wheels or disks 17 each rotating with a shaft 18. In the bottom of the tank is a pool of liquor generally maintained at the level indicated in

2

Fig. 1. The chamber 10 has an inlet 20 and an outlet 21 which connect the flue gas outlet of a sulphate furnace waste heat boiler and to a stack or induced draft fan, respectively. The flue gases from the waste heat boiler flow through the top portion of the casing. Each baffle wheel is separately rotated through a pulley 22 connected by a belt or chain 23 with a pulley 24 driven from a motor 25 through reduction gears 26.

The gases from the recovery furnace and the waste heat boiler contain quantities of sodium sulphate and sodium carbonate. When these gases impinge on the wetted baffles of the evaporator the chemicals adhere to the baffles and are thus scrubbed out of the gases. Should stratified scrubbing occur, lumps are apt to form. Furthermore, the liquor in the evaporator is generally at a temperature not far above the point where congealing of the liquor can occur. Should there be any regions in the quiescent corners or recesses of the evaporator where cooling may take place, small quantities of liquor will congeal and form lumps. Liquor splashed on the walls of the evaporator forms a solidified coating and at irregular intervals portions of the latter break off and fall to the bottom of the tank. These lumps collect in the quiescent regions between the baffle wheels and the bottom of the tank and between the wheels and the bottom corners of the tank. Unless these accumulations are removed they grow into piles until these may seriously interfere with the operation of the baffle wheels. Heretofore these piles have been raked out periodically by hand, which cleaning interrupted the continuity of operation of the evaporator. With the increased capacity of recovery units, lump removal thus became a serious interruption.

In the past the baffle wheels of the evaporators all revolved in a clockwise direction, as viewed in Fig. 1. As a consequence the fluid circulated along both side walls of the tank in the same direction, the two streams mingling to flow back through the center of the tank from one end to the other. According to the invention two of the groups of wheels are rotated in reverse direction with respect to the other two. Referring to Fig. 2, wheels 12 and 13 have their driving connections arranged for counterclockwise rotation while wheels 14 and 15 are revolved clockwise. The liquor in the bottom of the tank is then advanced by wheels 12 and 13 toward the right and by wheels 14 and 15 toward the left. There will also be cross flow of the liquor at the ends of the tank from the wheel 14 toward the wheel 12 and from the wheel 13 toward the wheel

15. In this way the liquor is continuously moved in a current running counterclockwise around the tank, as viewed in Fig. 2.

To further agitate the liquor in the quiescent corners and to aid this current helical screws 30 and 31 and paddle wheels 32 are provided. Screw 30 is located below and alongside baffle wheels 12, 14 in the left hand lower corner of the tank and is rotated by pulley 33 and belt 34 from the shaft 6 of the baffle wheel 12 so that it turns counterclockwise. Paddle wheel 32 is driven by pulley 35 and belt 36 and pulley 31 from the shaft of baffle wheel 13 and also turns counterclockwise. The screw conveyor 32 is driven by gears 37 from one set of reduction gears 26 so as to turn counterclockwise. As mentioned the screws 30 and 31 and paddle wheel 32 are so placed as to be where the lump piles accumulate. The helixes of the screws 30 and 31 are so arranged that as they turn they move the solid material in the direction of the liquor current. In this way the piles are prevented from forming and the material is given a general movement in the direction of the liquor current. This keeps the particles in flotation and the general current flow tends to maintain a uniform temperature of the liquor in all parts of the tank and thereby avoids congealing and lump deposits which occurred heretofore. In place of the spiral agitators 30, 31 paddle wheels like that designated 32 may be employed in installations where the reverse movement of the baffle wheels affords ample circulation.

What I claim is:

1. In an evaporator having a tank containing a pool of black liquor or the like, a gas inlet and outlet at opposite ends of said tank above the level of liquid in said pool for circulating gas longitudinally through the tank; pairs of baffle

wheels rotatable on aligned axes extending transversely of said tank adjacent either end thereof; means for rotating the baffle wheel of each pair that is located adjacent the front wall of the tank in one direction and the other wheel of each pair that is located adjacent the rear wall of the tank in the opposite direction for causing circulation of the liquid in a definite path around the tank; and rotatable agitators disposed below the liquid level on axes parallel to said baffle wheels and in locations between either end of the tank and the baffle wheels adjacent thereto for preventing deposit of material solidified from said pool and moving it away from said locations.

15. 2. In an evaporator having a tank containing a pool of black liquor or the like, a gas inlet and outlet at opposite ends of said tank above the level of liquid in said pool for circulating gas longitudinally through the tank; pairs of baffle

20. wheels rotatable on aligned axes extending transversely of said tank adjacent either end thereof; means for rotating the baffle wheel of each pair that is located adjacent the front wall of the tank in one direction and the other wheel of each pair that is located adjacent the rear wall of the tank in the opposite direction for causing circulation of the liquid in a definite path around the tank; and rotatable agitators disposed below the liquid level on axes parallel to said baffle

25. wheels and in locations between either end of the tank and the baffle wheels adjacent thereto for breaking up material solidified from said pool and means for rotating said agitators so as to cause them to move said material in the same

30. 35. direction as that of the fluid circulation in said tank.

CHARLES RICHARD PERCIVAL CASH.
